LUGGAGE CONSTRUCTION

Walter Blalo, New Rochelle, N.Y.
(836 Broadway, New York, N.Y.)
Filed Jan. 26, 1960, Ser. No. 4,669
1 Claim. (Cl. 190—49)

The present invention relates to a luggage construction, and it particularly relates to a hand luggage construction.

Although not restricted thereto and also suitable for various types of carrying cases or receptacles, the present invention will be particularly described in its application to leather or fabric type luggage construction in which the leather is mounted upon an extruded lightweight metal frame.

The frame is desirably of lightweight aluminum or other lightweight metal or alloy, but it also may be made of hard stiff plastic or even of steel, particularly stainless steel.

In normal luggage constructions, the metal frame parts are wrapped or encased in thin fabric or leather and the thick leather or fabric of the body itself is stitched to the projecting edges of the bag or luggage construction.

This construction is expensive, readily subject to damage and is cumbersome and greatly increases the costs and weight of the luggage construction.

It is among the objects of the present invention to provide a simple durable readily manufactured lightweight luggage construction which will be strong, not readily subject to damage and which not only is applicable to luggage per se, but also to various other container constructions, such as hat boxes, briefcases, camera cases, toilet kits and the like.

Another object is to provide a novel luggage construction in which the metal frame shall constitute part of the exterior structure of the luggage as well as the interior structure thereof so that the entire leather material as well as the frame structure constitutes an integral structure of great strength and of pleasing appearance.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most satisfactory according to one embodiment of the present invention to provide a frame structure which will consist of two rectangular frame members of extruded lightweight metal, such as aluminum or aluminum alloy, and less desirably stainless steel and in which there will be a central transverse body structure with adjacent male and female overlapping wedging members and outwardly extending relatively thin members to which the leather or other fabric constituting the leather, may be directly stitched.

In the preferred form of the invention, the exterior includes a relatively thin, flexible section extending transversely to the plane of the frame upon which the edges of the leather or other leather like material are positioned and stitched.

The other portions are much thicker and more subject to flexibility, and they form an overlapping wedged structure together with vertical integral members constituting the connection between the telescoping wedge section and the thin fins to which the leather is stitched.

With the foregoing and other objects in view, the invention consists of the novel construction, combination and arrangement of parts as hereinafter more specifically described and illustrated in the accompanying drawings, wherein is shown an embodiment of the invention, but it

2

is to be understood that changes, variations and modifications can be resorted to which fall within the scope of the claim hereunto appended.

In the drawings wherein like reference characters denote corresponding parts throughout the several views:

FIG. 1 is a top perspective view of a typical piece of luggage particularly broken away more clearly to show the interior structure, said luggage being in closed position.

FIG. 2 is a top perspective view showing the two halves of the luggage of FIG. 1 in open position showing the interior construction.

FIG. 3 is a fragmentary transverse sectional view of the telescope frames upon an enlarged scale showing the manner of attachment of the leather and the manner in which the frames meet, when they are about to telescope together.

FIG. 4 is a fragmentary transverse sectional view similar to FIG. 3 in which the frames have been completely closed together with the frames in their final abutment position.

FIG. 5 is a fragmentary side perspective view showing the cross section of the frame, enlarged as compared to FIGS. 3 and 4; FIG. 5 being a showing of the male member.

FIG. 6 is a similar fragmentary perspective view like FIG. 5 showing an end of the frame construction.

Referring to FIGS. 1 and 2, there is shown a luggage structure having the male frame member A and the female frame member B each of rectangular shape which are enclosed, carried by a leather or leather like body C forming a container section and a cover section.

The cross section of the male frame member A and the female frame member B approximates an X or a T.

Two of the opposite flanges at the head of the T or the opposite legs of the body of the X extend away from each other and are approximately parallel to each other and are relatively thin so that they may be stitched to the leather or leather-like fabric forming the body C.

The opposite parallel legs which may be considered as positioned horizontally for the purpose of this description and which are parallel to the stitching flanges are heavier in cross section and are thicker so that they will be more rigid and they have adjacent bevel or oblique

faces and they telescope over one another with a wedging effect, with the male and female members coming together until they substantially meet at the crossing point of the X or at the crossing of the stem and the top of the T, depending upon which cross section more

aptly describes the cross section of the frame members A and B. In either case, the stem of the T or the intermediate legs of the X are relatively heavier and of thicker material so that they will constitute the principal rigid body at the center of the frame members and

this stem of the T or opposite legs of the X cross section will be substantially perpendicular or transverse to the stitching flanges and to the telescoping male and female flanges and they may be considered for the purpose of this description as extending perpendicularly or vertically to the stitching flange and the overlapping male and female flanges.

In closed position the male and female flanges will abut the center stem or central legs of the T or X cross section, as the case may be, and the two frames will be wedged together in relatively tight position.

In the initial engagement the male and female flanges of the X or T cross section will first contact each other along their adjacent oblique or bevel faces and then will slide up over one another until they are wedged together.

The frames carry the hinges D which are mounted upon the base of the luggage and they also are provided with the lock E and the handle F.

The hinges D, the lock E and the handle F may also be attached to the rectangular frame structures A and B.

The invention, however, is particularly directed to the actual construction of the frame members A and B, and to the manner in which they telescope together, and to the attachment of the covering material whether leather or synthetic fabric to the frames, and by the use of the word "leather," is included leather like material, synthetic fabrics, cloth or various types of plastics which serve as substitutes thereof or imitation of leather body materials.

Referring particularly to the male section A, as shown in FIGS. 3 to 5, there is a first heavy base member 10 of extruded aluminum having an upwardly projecting edge or top end 11 extending away from the luggage construction and a downwardly projecting edge or bottom end 12 extending into the mouth portion of the luggage construction.

Extending in the telescoping direction is the first telescoping flange member 13 having a heavy base portion 14 with a sloping or oblique surface 15 and a straight perpendicular surface 16.

From the other side of the first heavy base member 11 is the thin flexible readily penetrating fin or first thin flange member 17 to which the edge 18 of the leather may be stitched as indicated at 19 directly adjacent to and in close proximity to the first heavy base member 10.

Although this fin 17 may be of slightly extra thickness at 20, adjacent to its junction to the first heavy base member 10, it is desirably of uniform thickness throughout and is relatively flexible as compared to the thick sections of the first heavy base member 10 and the first telescoping flange member 13.

Referring now to the female member as shown in FIGS. 3, 4 and 6, this member has a second heavy base member 21 with a relatively heavy rigid bottom end 22 extending inwardly.

The top end of the second heavy base member 21 carries the inturned overlapping second telescoping flange member 23 which also has a relatively thick base portion 24 with the straight transverse top surface 25 and the oblique wedging bottom surface 26.

It will be noted that the second telescoping flange member 23 has a base face 27 which is offset inside of the face 28 of the second heavy base member 21.

The oppositely directed second thin flange member or fin 29 corresponds, to the first thin flange member 19, and it is flexible and penetratable.

The edge 30 of the leather or other covering material is stitched as indicated at 31 to the second thin flange member 29 at 32 adjacent the first heavy base member.

The position of the frames A and B is such that when they are initially closed together, the edge 33 as shown in FIGS. 3 and 6 will contact the oblique surface 16 of the first telescoping flange member 13 and will then slide from the position of FIG. 3 to the position of FIG. 4 until the face 34 of the frame B contacts the face 35 of the frame A (see FIG. 4).

At the same time there will be a contact or stop between the face 36 of the first heavy base member 13 and the oblique surface 37 of the second heavy base member 21.

The telescoping connection as shown in FIG. 4 will tend to force the frame B outwardly and the frame A inwardly at the stiff or non-flexible side thereof without greatly affecting the relatively thin first and second thin flange members 17 and 29.

The fabric or leather edges 18 and 30 may be directly stitched by the stitching 19 and 31 with a cylinder type chain stitch sewing machine having heavier gears and with an awl shaped needle.

The frame members, which include a male frame member A and a female frame member B, are of T cross section, as indicated in FIGS. 5 and 6, with the over-

lapping female leg 25 and male leg 15 constituting wedging members to wedge the structures together tightly upon closing, with the wedging starting at a point along the inclined surface indicated at 33 in FIG. 3 and with the female flange 23 sliding up until the abutment at 35, at which point the edge 36 of the male member 16 will abut the central abutment flange of the T structure, as indicated best in FIG. 4.

This wedging and sliding action takes place during the telescoping of the female leg or member 23 as it slides up on the male member 16 into the abutment position of FIG. 4.

The opposite legs 17 and 29 of the T cross sections, which are approximately parallel to but oppositely directed from the male and female wedging flanges 16 and 23 are much thicker so that the fabric portions 18 and 30 may overlay and also abut the central structural stem members and be stitched in position. The central members 10 and 21 are of relatively heavy stock and they are integral with the overlapping male and female flanges 16 and 23 and the stitching flanges 17 and 29 and they constitute the stem of the T structure or T cross section.

Although various types of heavy duty sewing machines may be employed, it has been found that a "Puritan" XL cylinder machine adapts itself to the position employing a single thread and producing a chain stitch.

These machines are desirably provided with a sturdy awl which is forced through the thin flexible flanges 17 and 29 in one direction and withdrawn.

As the awl is withdrawn, the needles moves in or follows the awl from the opposite side of the material and enters the hole made by the awl.

The flanges 17 and 29 are desirably about $\frac{1}{4}$ to $\frac{2}{3}$ and desirably about $\frac{1}{2}$ the thickness of the heavy flanges 13 and 23 which telescope together.

Although the vertical body elements may be made of intermediate thickness, they desirably are of the slightly greater thickness than the flanges 17 and 29 to which the stitching is applied.

In the preferred construction, the thin flanges 17 and 29 may be made of thicknesses varying from 0.020" to 0.045", but preferably about 0.035", and the vertical members 10 and 21 may be made of similar thicknesses.

This thickness will enable ready penetration and stitching with an awl-type machine.

Normally, the sewing machine is modified so as to increase the power of the motor as well as the cross section of the drive belt between the motor and the sewing machine.

In one preferred form, the wall thickness of the vertical members 10 and 21 may be from 0.035" up to 0.062" and the thick base 14 of the flange 13 may be twice the thickness of the flanges 17 and 29.

The top faces of the thin flange members 17 and 29 are desirably displaced sufficiently below the top face of the flange 23 and the top edge of the first heavy base member 10 so that the top face of the covering material may be substantially flush, although slightly below the top of the vertical or body member 10 and the top face of the flange 23 as shown in FIG. 3.

The metal of the frames A and B is desirably extruded and extends continuously around the top and sides of the luggage as indicated in FIGS. 1 and 2, and it will be split at the middle of the bottom at the position of the middle hinge D as shown in FIG. 2.

As indicated in FIG. 2, the split may be covered by a junction plate 55 riveted to the split ends.

The bottom boards 56 which extend from the frames A and B to the outer edges 57 are added for reinforcement and stiffening purposes, and they may be riveted into position by the connection of the hinges D.

The leather or other synthetic fabric material desirably extends in strips 58 and 59 around the frames A and B, with its edges stitched as indicated at 19 and 31 in

FIG. 3, and it is attached by riveting, stitching or both at 60 and 61 (see FIG. 1) to the side walls 62 and 63.

An inside covering material 64 and 65 may also be used to finish the inside of the luggage.

The actual alloy which may be used for the frames A and B may consist of the alloy known as 6063-T5 of the Aluminum Company of America.

An alloy consisting of 65 to 95% of aluminum has been found to be the best type of alloy, and it may be readily given color or luster by anodizing process.

The actual top surface of the second heavy base member 23 and the top end of the first heavy base member 10 will be exposed at the exterior of the luggage and will give an attractive contrasting appearance to the leather, fabric body.

In general, in the form shown, the telescoping sections are thicker and more rigid than the attachment flanges 17 and 29, but in view of the rectangular shape of the frames A and B and their rounded corners, it is possible to achieve sufficient flexibility so as to permit the wedging operation as indicated from positioning 3 to position 4.

The thickness of the neck at 66 in the female frame B will also aid in the wedging as shown in FIG. 4.

It will be noted that the flexibility or stiffness of the material of the frames A and B depends upon the thickness of the section and that each of the frames may be considered as having an X shape with one leg of the X consisting of a heavy base member forming the body from opposite sides of which project the thin flanges 17 and 29, and the telescoping flanges 13 and 23.

Although the extensions are both of X shape, they are so designed that one will telescope inside of the other with there being a wedging connection when the frames are closed together.

The wedging construction will give a greater rigidity and strength to the luggage without increasing the weight or bulkiness thereof.

Moreover the fact that the face 25 and the top edge of the first heavy base member 10 project slightly above the face of the leather will protect said leather against undue scuffing.

The turning or frame or extension at the four corners as shown in FIGS. 1 and 2, will also give extra strength and permit the wedging operation as indicated in FIG. 4.

No attempt is made to perforate the flanges 17 or 29 before the sewing machine operation, but the awl and stitching operation take place at the same time.

It is understood, that in addition to leather, it is possible to use fabric, canvas, laminated materials or even composite boards, and that the basic frame structure may be made hexagonal, circular, triangular, or various other shapes than rounded corners, rectangular, as shown in FIGS. 1 and 2.

Referring specifically to the cross section of the frame members, the frame members as shown in FIGS. 5 and 6 desirably consist of aluminum extrusions of aluminum alloy of the type known as X-1074 with a minimum hardness of 8 webster with a weight per running inch of about 0.007 pound.

The thin stitchable fins or thin flanges 17 and 29 have a width of about 0.562" and a thickness of about 0.033" in the preferred embodiment.

Desirably, both thin flanges 17 and 29 may be of the same thickness and width.

The heavy base members 10 and 21 desirably have a thickness of about 0.047" in the preferred embodiment whereas telescoping flange members 13 and 33 may have a terminal thickness of about 0.058", and they may thicken at their base or root adjacent the heavy base members 10 and 21 to about a thickness of 0.085" to 0.1".

If desired, both the top of the telescoping flange members 13 and 33 may be crowned or rounded, although they may also be flat as shown.

As many changes could be made in the above luggage construction, and many widely different embodiments of

this invention could be made without departing from the scope of the claim, it is intended that all matter contained in the above description shall be interpreted as illustrative and not in a limiting sense.

Having now particularly described and ascertained the nature of the invention, and in what manner the same is to be performed, what is claimed is:

A substantially rectangular luggage construction comprising a container section and a cover section, each of said container and cover sections having a mouth portion, a substantially rectangular frame member circumscribing each mouth portion, an enclosure portion and a flexible fabric covering material surrounding said enclosure portion; a hinge means pivotally connecting said container and cover sections so that said luggage construction may be in an opened position with said mouth portions being separated and in a closed position with said mouth portions being in juxtaposition to each other; the substantially rectangular frame member of said container section having in cross section a first heavy base member positioned in a plane parallel to the plane of the mouth portion of said container section, said first heavy base member having a top end extending away from said mouth portion and a bottom end extending into said mouth portion, an integral first thin flange member extending inwardly of said container enclosure portion and having a top surface in a plane perpendicular to the plane of said first heavy base member and spaced a distance slightly in excess of the thickness of said flexible fabric from said top end of said first heavy base member, and an integral first telescoping flange member extending outwardly of said container enclosure portion and having a top surface, a bottom surface, and an outer end, said top surface of said first telescoping flange member being in a plane which is oblique to the plane of said first heavy base member and intersecting said first heavy base member at a point which is a predetermined distance from said top end of said first heavy base member; the substantially rectangular frame member of said cover section having in cross section a second heavy base member positioned in a plane parallel to the plane of said mouth portion of said cover section, said second heavy base member having a top end extending away from said mouth portion and a bottom end extending into said mouth portion, an integral second thin flange member extending inwardly of said cover enclosure portion and having a top surface in a plane perpendicular to the plane of said second heavy base member and spaced a distance slightly in excess of the thickness of said flexible fabric from said top end of said second heavy base member, and an integral second telescoping flange member extending outwardly of said cover enclosure section and having a top surface, a bottom surface, and an outer end, said outer end being slightly less in thickness than said predetermined distance, said top surface of said second telescoping flange member being in a plane which is perpendicular to said second heavy base member and in line with said top end of said second heavy base member, said bottom surface of said second telescoping flange member being in a plane which is oblique to the plane of said second heavy base member; the flexible fabric covering material of said container enclosure section being stitched to the top surface of said first thin flange member, and the flexible fabric covering material of said cover enclosure section being stitched to the top surface of said second thin flange member, the top surfaces of said first and second thin flange members being in the same plane and aligned with each other when said luggage construction is in said closed position, the oblique bottom surface of said second telescoping flange member being in a plane which is less oblique than the plane of the oblique top surface of said first telescoping flange member, the oblique top surface of said first telescoping flange member being contacted at a point between the outer end of said first telescoping flange member and the first heavy base member by the oblique bottom surface of said second telescoping flange member.

ing flange member to provide a wedging action as said luggage construction is being closed; the outer end of said first telescoping flange member being in abutting relationship with said second heavy base member and the outer end of said second telescoping flange member being in abutting relationship with said first heavy base member when said luggage construction is in said closed position.
